CLAIM

The ornamental design for a semiconductor device, as
shown and described.

DESCRIPTION

FIG. 1 is a front, top and right side perspective view of a
semiconductor device, showing our new design;

FIG. 2 is a front elevational view thereof; the opposite side
being a mirror image thereof;

FIG. 3 is a right side elevational view thereof; the opposite
side being a mirror image thereof;

FIG. 4 is a top plan view thereof; and,

FIG. 5 is a bottom plan view thereof.
